ELECTRICAL CONNECTOR

Herbert M. Rogers, Canton, Ohio, assignor to The
Hoover Company, North Canton, Ohio, a cor-
poration of Ohio

Application June 24, 1943, Serial No. 492,005

1 Claim. (Cl. 174—46)

1

The present invention relates to an electrical connector such as can be used within a hollow tubular handle of a suction cleaner.

An object of the invention is to provide a new and improved electrical connector. Another object is to provide novel means for anchoring the electric contact in the body of the electrical connector and to secure an electric cord to the contact. Another object is to provide an inexpensive electric contact having a slotted end for the fastening means to secure the contact in the plug body. Further objects and advantages of the invention will be apparent from the following specification and drawings wherein:

Figure 1 is a vertical section, partly in elevation, through the handle and socket of a suction cleaner;

Figure 2 is a section along the line 2—2 of Figure 1;

Figure 3 is a section along the line 3—3 of Figure 2;

Figure 4 is a perspective view, partly in section, showing the interior construction of the plug cap body, and

Figure 5 is an exploded perspective view, partly in section, of the plug cap.

The embodiment of the invention herein disclosed comprises the lower end of a hollow tubular suction cleaner handle 10 removably inserted in the tubular portion 11 of a split handle clamping socket 12 terminating at its lower end in an enlarged portion 13 having opposed walls 14 which are pivotally supported on an unshown cleaner body in a manner well known in the art.

Disposed in the lower end of the handle is a plug socket 15 having a body provided with a flanged end 17 which rests against the extreme lower edges of the handle 10, a body portion 18 snugly engages the inner surface of the hollow handle, and a reduced body portion 19 receives the power leads 20, 20 extending upwardly in the handle to a switch, not shown, for controlling the circuit from a power source to the suction cleaner motor. A pair of suitable contacts 21 are mounted in the socket and are connected to the power leads 20, 20. The socket is rigidly mounted in a predetermined position in the handle by a pair of pins 22 passing through the handle and the socket body to arrange the contacts 21 one above the other in a vertical plane passing through the longitudinal center of the handle.

Disposed in the handle socket 12 is a plug cap 25 having a cylindrical body 26 provided with a pair of spaced contact receiving openings 27 of substantially rectangular cross-section and which

2

extend from one end face 28 of the body 26 inwardly of the latter to a shoulder 29 formed by a portion 30 of the plug body. A circular opening 31 is provided in each of the portions 30 of the plug cap body and extends from an enlarged recess 32 at the opposite end of the body 26 to the rectangular opening 27, and opposed walls of each rectangular opening 27 are provided with arcuate recesses 33 to form a continuation of the circular opening 31. The recess 32 spans the circular openings 31 and is formed with an end wall 35 and an irregularly shaped peripheral wall 36.

A contact 37 of elongated rectangular cross-section is snugly disposed in each rectangular opening 27 and has its inner end 38 abutting the shoulder 29 and its outer end extending beyond the end 28 of the plug cap. The inner end of each contact is provided with a non-annular slot which is broached or threaded as at 44 for the reception of a screw 40 which passes through the circular opening 31. Motor leads 41, 41 extending from the unshown motor are each connected to one of the contacts 37 by means of an eyelet 42 disposed about the screw 40 between the screw head 43 and the end wall 35 of the recess 32. The non-annular slot 44 in each contact 37 provides an inexpensive contact and means for securing the latter and the cord in the plug body, since it is not necessary to form an enlarged contact portion for the fastening screw 40. The slots 44 may be formed by stacking a plurality of contacts in alignment and cutting the slots in one operation and thereafter broaching the slots. If desired a block of metal may be slotted and the slots broached and thereafter the block of metal may be cut to provide the individual contacts 37.

In assembling the contacts 37 and screws 40 in the plug cap, the cross-section of the rectangular openings 27 prevent the contacts from rotating and the exposed threaded portions of the fastening screws 40 which extend laterally beyond the thickness of the contacts 37 are accommodated by the arcuate recesses 33 in the rectangular openings 27. The contacts 37 and motor leads 41 are rigidly connected together by the screws 40, the latter drawing the inner ends 38 of the contacts 37 against the shoulder 29, and the eyelets 42 of the motor leads rigidly between the screw heads 43 and the end wall 35 of the recess 32. The open end of the recess 32 is closed by an insulating plate 45 which has its peripheral edge 46 contoured to fit snugly within the recess 32 and is provided with an elongated opening 47 to receive the motor leads 41.

The plug cap 25 is supported in the handle socket 12 by a substantially U-shaped bracket 50 having its side walls 51 attached to the side walls 14 of the enlarged portion 13 of the handle socket 12 and its bight portion 52 extends between the socket side walls 14. A portion 53 of the bracket 50 extends into a marginal recess 54 of the plug cap 25 and the latter is rigidly secured to the bight portion 52 by means of a screw 55 threaded into an opening 56 in the plug cap body 26 to properly position the plug cap in the handle socket.

Arranged about the motor leads 41 is a cord protector 60 having a reduced portion 61 passing through an opening 62 in the bight portion 52 of the bracket 50, and having an enlarged portion 63 disposed between the bight portion 52 and the insulating plate 45 to thereby retain the cord protector in proper position.

In order to insert the plug cap 25 in the handle socket 12, the motor leads 41 are connected to the contacts 37, and then the cord protector 60 is placed over the motor leads with its enlarged end 63 adjacent the insulating plate 45. The reduced end 61 of the cord protector is passed through the opening 62 in the bracket 50, and the plug cap 25 and cord protector are held rigidly in position in the handle socket by means of the screw 55, and the opposite ends of the motor leads may be connected to the cleaner motor. The contacts 37 are arranged in predetermined position in the handle socket 12 by means of a portion 53 of the bracket 50 being disposed in the marginal recess 54 of the plug cap 25. Thereafter the handle 10 with the plug socket 15 can be inserted in the handle socket 12 and the contacts 37 connected with the contacts 21 of the plug socket 15 to complete the electrical connection between the motor leads 41 and the power leads 20.

I claim:

An electrical connector, comprising an insulat-

ing body having a passageway, an apertured shoulder in said passageway, an electrical contact of rectangular cross-section in said passageway, said passageway at one side of said apertured shoulder having a rectangular cross-section corresponding to said electrical contact to prevent rotation of the latter therein, a threaded non-annular slot at the anchor end of said electrical contact, a screw in said body having its head abutting said apertured shoulder on the other side thereof and the threaded portion of said screw in said non-annular slot of said electrical connector, whereby tightening of said screw draws said anchor end of said electrical contact against said one side of said apertured shoulder and said screw head against said other side of said shoulder to hold said contact in said body, said anchor end of said electrical contact having a thickness in one section thereof less than the diameter of said screw whereby portions of the latter project radially outwardly of said electrical contact, and said passageway having a recess to receive said portions of said screw projecting radially outwardly of said electrical contact.
